UNITED STATES PATENT OFFICE.

ADOLPHE PICHA, OF GHENT, BELGIUM.

PAVING-TILES.

SPECIFICATION forming part of Letters Patent No. 739,345, dated September 22, 1903.

Application filed April 16, 1902. Serial No. 103,076. (No model.)

To all whom it may concern:

Be it known that I, ADOLPHE PICHA, manufacturer, a subject of the King of Belgium, residing at 54 Boulevard Lousbergs, Ghent, 5 in the Kingdom of Belgium, have invented certain new and useful Improvements in Paving-Tiles, of which the following is a specification.

This invention relates to the manufacture 10 of tiles for forming pavements, and relates more particularly to the manufacture of tiles for producing the effect of tessellated work or mosaic.

The object of the invention is to obviate 15 in pavements of this kind the production of visible joints, which by uniformly cutting the design which the pavement is intended to form are very much in evidence and prejudicially affect the appearance of the design.

20 The invention consists, essentially, in imparting to the tiles irregular contours or edges, thus producing projections and indentations following the contours of the mosaic or other design in such a manner that when 25 the tiles are assembled the joints occupy various directions, so that the eye cannot distinguish them from the contours formed upon the plane surface of the tiles.

In the accompanying drawings a method 30 of carrying my invention into practice is illustrated by way of example.

Figure 1 shows four tiles intended to enter 35 into the composition of an imitation mosaic pavement. Fig. 2 shows the variation of my device, displaying the tiles with the irregular-shaped bases.

As shown in the drawings, the tiles *a b c d* 40 instead of being formed with regular edges in the ordinary manner are formed with edges *e*, which follow the contours of the designs formed upon the surface of the tiles. These sides consequently present projections *f* and indentations *g*, which when the tiles are 45 assembled produce a mathematically regular and perfect fit.

It will readily be understood without further explanation that under these conditions the joints are not distinguishable from the contours of the designs formed upon the 50 surface of the tiles and that by means of tiles of this kind a perfect design may be obtained, the appearance of which is in no wise disfigured by the joints of the various tiles constituting the pavement.

My method of manufacturing tiles may be 55 varied to some extent without departing from the spirit of my invention. For example, irregular-shaped tiles may be formed of a homogeneous material having figures or designs of one or more colors incrusted upon 60 their surfaces, and these may be fitted together as contemplated in my method in any desired arrangement.

Another variation contemplated by my invention is to form the base of the tile of any 65 suitable material and to place upon this base, so as to completely cover the same and to conform to its contour, the fragments of different colors and different substances suitable for a mosaic work, as marble, asphalt, 70 or metal pieces. These base-pieces are then put together as with my first-described tiles, the projections of one base engaging with the recesses of the adjacent ones.

What I claim, and desire to secure by Letters Patent of the United States, is—

1. A device of the type set forth comprising a plurality of tiles, each provided with edges outwardly extending in various directions and irregular recesses formed between the outwardly-extending portions, said tiles adapted to fit together, the extended portions of one tile fitting into the recesses of the other, whereby a complete design is formed, the points thereof being indistinguishable, substantially as described.

2. In tiles for producing the effect of tessellated work or mosaic the combination of an irregular-shaped base with a plurality of irregular-shaped pieces carried by said base substantially as and for the purpose specified.

3. In tiles for producing the effect of tessellated work or mosaic the combination of an irregular-shaped base with a plurality of irregular-shaped pieces carried by said base and so arranged that they completely cover said base while rigidly following its contour substantially as and for the purpose specified.

In testimony whereof I have hereunto set my hand, in presence of two subscribing witnesses, this 24th day of March, 1902.

ADOLPHE PICHA.
